UNITED STATES PATENT OFFICE.

THOMAS OLINGER, OF HOLLAND, MICHIGAN, ASSIGNOR TO FEDERAL STAMPING COMPANY, OF HOLLAND, MICHIGAN, A CORPORATION OF MICHIGAN.

FURNACE-REGULATOR CONSTRUCTION.

Application filed September 5, 1922. Serial No. 586,109.

To all whom it may concern:

Be it known that I, THOMAS OLINGER, a citizen of the United States of America, residing at Holland, in the county of Ottawa 5 and State of Michigan, have invented certain new and useful Improvements in Furnace-Regulator Constructions; and I do hereby declare the following to be a full, clear, and exact description of the invention, such as will enable others skilled in the art to which it appertains to make and use the same.

This invention relates to a furnace regulator construction for use in changing the drafts in furnaces from an upper room, the furnace usually being located in the basement. The present construction is wholly of sheet metal except for the spring and cotter pin used in connecting the spring 15 in place and may be manufactured at low cost. The assembly is simple and the construction when assembled occupies little 20 space, is easily operated and frictionally holds any position to which operated. It 25 is an object and purpose of this invention to produce a regulator construction of this type and one which can be manufactured in quantity at low cost, all parts except stock parts which are obtained at low cost, being 30 readily formed on punch presses by means of suitable dies with great rapidity. The construction illustrated in the drawing has all of these features of advantage, as well 35 as many others tending to make a practical, durable and efficient article for the purposes described, as will appear from an understanding thereof from the following description taken in connection with said drawing, in which,

Fig. 1 is a perspective view of the complete regulator construction.

Fig. 2 is an enlarged vertical section taken transversely therethrough.

Fig. 3 is a fragmentary plan of the central part of the outer enclosing member of the construction.

Fig. 4 is a like view of the inner operating member.

Fig. 5 is a perspective view of the operating handle, and

Fig. 6 is a perspective view of a connecting member between the handle and inner operating member.

Like reference characters refer to like parts in the several figures of the drawing.

In the construction, an outer covering or enclosing member of sheet metal is used, comprising a front 1 of circular outline, at the edges of which a reinforcing bead 2 may be formed, from which sides 3 may be turned inwardly at right angles for a short distance, and then turned outwardly to make an annular flange 4, at two diametrically opposed points in which enlarged ears 5 are formed through which suitable fastening devices are adapted to be passed into any suitable support for the regulator. In opposite points of the sides 3, openings 6 are made for the passage of the chains leading to the furnace check and draft doors 70 in the usual manner.

Adjacent the center of the front 1 an annular outwardly extending rib 7 is made, its inner sides 8 extending inwardly at an angle, as shown, and surrounding a central 75 circular opening 9 in said front 1.

Associated with the outer covering member is a movable inner operating member, also of sheet metal and including a front 10 of less diameter and substantially paralleling the front 1 of the cover member, it may also be formed with a reinforcing bead 11 at its edges, from which sides 12 extend inwardly for a short distance, there being an annular out-turned 80 flange 13 formed at the inner edges of the sides 12. Tongues 14 may be struck from the flange 13 and the side 12 at the upper side of the operating member to connect the chain 15 thereto, the chain passing 85 partly around the operating member and out through openings 6.

The front 10 of the inner member is likewise formed with an annular outwardly projecting rib 16 near its center which fits in the groove made by the rib 7 in the cover member, its inner inclined sides 17 extending beyond the inclined inner sides 8 of the rib 7 and joining with a central web 18 set farther in and in a plane paralleling the front 10. An elongated slot 19 is made through the web 18, as shown in Fig. 4.

The operating handle is made from a flat piece of sheet metal at one end formed into 100 disk-like shape, as at 20, with inturned edges 21 to fit against the outer inclined sides of the rib 7, an elongated opening 22 is made therethrough similar to opening or slot 19 previously described. From said end 110

the handle extends as a bar 23 which is provided with side flanges of progressively increasing width outward turned at right angles, as indicated at 25, the outer ends of which are enlarged to make finger engaging ears 26.

The inner member of the regulator construction is placed inside the outer member with its rib 16 seated in the groove on the inner side of the rib 7 of the cover member, the operating handle 23 is then placed over the rib 7, its end covering the opening at 9, and the openings 24 and 19 are positioned in alinement. When so positioned, the flanges 25 and finger engaging ears 26 extend inwardly, the ears extending alongside the sides 3 of the outer cover member. A connecting member 27 formed from flat metal is passed through the alined slots, at its outer end having a wider head 28 which bears against the inner end of the handle. An opening 29 is made through the inner end of member 27. A coiled spring 30 is placed around the member 27, at one end seating in the groove of rib 16, and a cotter pin 31 is passed through opening 29 against which the outer end of the spring bears. This completes the assembly of the regulator construction and it is ready for operation, it being understood that the chain 15 is connected to the inner operating member before assembly if desired or it may be attached later.

This construction of regulator has the inner member bearing against the outer member through the force of spring pressure exerted by the spring 30 where the ribs 7 and 16 have contact engagement, and the friction of such engagement holds the parts yieldingly in any position to which they may be moved. The inner and outer member, the operating handles and connecting member 27 are all easily produced in quantity by punch press operations, while the spring and cotter pin are produced by makers thereof by automatic machinery and can be bought in quantity at low price. This makes the regulator construction one very economical to manufacture, as the assembly is very simple. The inturned ears 26 on the operating handle afford plenty of surface for engagement by the fingers in operating the construction and the space occupied is reduced to a minimum and no projecting parts are left against which accidental engagement may be made. The construction is simple, practical, durable and efficient in every way. The invention is defined in the appended claims and is to be considered as comprehending all forms of structure coming within their scope.

60 I claim:

1. A furnace regulator construction comprising an outer member of cup-like form made from a single piece of sheet metal, said member having a front formed with an annular outwardly projecting rib and a cen-

tral opening around which said rib is formed, an inner member of like form having a front with an annular outwardly projecting rib to seat in the groove of the rib of the first member, and a web extending across between the inner edges of the inner sides of said rib, said web being located at the center of said front of the inner member and having an elongated opening therethrough, an operating handle formed with inturned side flanges which at their outer ends are enlarged to form finger engaging ears and at its inner end into disk-like shape to fit over the rib on the outer member said inner end also having an elongated opening therethrough, said handle being located over the outer member with said ears turned inwardly and with the openings in the handle and inner member in alinement, a connecting member formed as a flat bar with a wider head passed through said openings, a coiled spring around the connecting member seated at one end against the rear side of the front of the inner member, and a cotter pin passing through the inner end of the connecting member against which the opposite end of the spring bears, substantially as described.

2. A furnace regulator construction comprising an outer and an inner member of cup-like form, the inner member being located within the outer member, interengaging annular ribs on the members around the centers thereof, said outer member having a circular opening therethrough within its annular rib and said inner member having an elongated opening therein within its rib, a handle member formed with an elongated opening therethrough at one end located at said end over the opening in the outer member and extending outwardly therefrom, said openings in the handle, an inner member being in alinement, a connecting member of flat metal formed with a wider head passed through said openings, a coiled spring around the connecting member within the inner member and bearing at one end against said inner member, and means connected to said connecting member against which the opposite end of the spring bears, substantially as described.

3. A furnace regulator construction comprising an outer and an inner member of sheet metal of cup-like form, the inner member being located within the outer member, interengaging friction means on the said members adjacent and around their central portions, said outer member having a central opening therethrough and said inner member an elongated opening therethrough inside of said means on the members, a handle member with an elongated opening through one end located at said end over the central portion of the outer member and extending outwardly, a connecting member

having a head thereon passing through both of said openings, a coiled spring around the connecting member within the inner member and bearing at one end against said member, and means connected to the inner end of said connecting member against which the opposite end of the spring bears, substantially as described.

4. A furnace regulator construction, comprising an outer and an inner member of cup-like form, the inner member being located within the outer member, interengaging friction means on said members adjacent and around their central portions, a handle located on the outer side of the outer member, means connecting the handle to the inner member and including a spring acting to press the engaging means of the inner member against said means of the outer member, said handle and inner member moving together, and said outer member having an opening passing the connecting means and permitting its free rotative movement with respect thereto.
5. A furnace regulator construction, comprising outer and inner members of cup-like form, each made from a single piece of sheet metal, the inner member being located within the outer member, interengaging friction means on said members adjacent and around their central portions, a handle for operating the inner member located outside of the outer member, and con-

necting means connecting the handle and inner member, said connecting means including a spring yieldingly forcing the inner member against the outer member at the interengaging friction portions thereof, substantially as described.

6. In a furnace regulator construction, inner and outer members, means for connecting said members for movement of the inner with respect to the outer member and to provide frictional contact engagement thereof, and a handle connected to the inner member and located at the outer side of the outer member, said handle at its outer end being provided with finger engaging means extending inwardly alongside the sides of the outer member, substantially as described.

7. In a furnace regulator construction, inner and outer members of sheet metal, means for connecting said members for movement of the inner member with respect to the outer member and to provide frictional contact engagement thereof, and a handle of sheet metal connected to the inner member and located at the outer side of the outer member, said handle having flanges at its sides enlarged at their outer ends and turned inwardly to lie alongside the sides of the outer member, substantially as described.

In testimony whereof I affix my signature.

THOMAS OLINGER.
